CLAIM

The ornamental design for holder for a shower brush or similar article, as disclosed.

DESCRIPTION

FIG. 1 is a front, top and right side perspective view of a holder for a shower brush or similar article showing my new design;

FIG. 2 is a right side elevational view thereof, the side opposite being a mirror image;

FIG. 3 is a rear elevational view thereof; and

FIG. 4 is a top plan view thereof.

The broken-line portions of each of the four figures are not part of, and are not included in, my new design, but are shown for orientation and environmental purposes only.
